Primary Examiner — Samantha Wood*Assistant Examiner* — Vanessa Martinez(74) *Attorney, Agent, or Firm* — Jose Cherson Weissbrot(57) **CLAIM**

The ornamental design for a clip-on light, as shown and described.

DESCRIPTION

FIG. 1 is a perspective view of a clip-on light showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top side view thereof;

FIG. 8 is a bottom plan view thereof;

FIG. 9 is a partial enlarged view of FIG. 1;

FIG. 10 is a partial enlarged view of FIG. 1; and,

FIG. 11 is a partial enlarged view of FIG. 1.

The broken lines in the figures are for the purposes of illustrating portions of the clip-on light, which form no part of the claimed design.
